UNITED STATES PATENT OFFICE

2,274,019

SWITCH

George Weider and Calvin Wilson, Charleston, W. Va., assignors of thirty-three and one-third per cent to Gerald G. Smith, Charleston, W. Va.

Original application May 13, 1939, Serial No. 273,539. Divided and this application April 24, 1940, Serial No. 331,468

1 Claim. (Cl. 200—52)

This invention relates to new and useful improvements in switches and is a division of my co-pending application Serial No. 273,539, filed May 13, 1939, for Electric counters.

An important object of the invention is to provide a switch structure which will be positive acting, sturdy in construction and not susceptible to the ready development of defects.

Other important objects of the invention reside in the provision of a switch structure which will be self resetting, operative in either direction by articles operating the same, ease of demountability for the purpose of repair or replacement of parts, rapidity of operation, and substantial fool-proofness in operation.

Other objects and advantages will be observed by the reader during the course of the following specification.

In the drawing:

Figure 1 represents a top plan view of the switch shown with its finger engaging the controlling article.

Figure 2 is a side elevational view of the switch.

Figure 3 is a cross section on the line 3—3 of Figure 2.

Figure 4 is a cross section on the line 4—4 of Figure 2.

Figure 5 is a perspective exploded view of the finger and mounting means therefor.

Figure 6 is a perspective view of the lower block of the mounting shown in Figure 5.

Referring to the drawing wherein like numerals designate like parts, it can be seen in the drawing that the switch consists of the base 17 from which rise the two brackets 18—18 and between which are the insulation blocks 18a. The two spring fingers 19—19 extend outwardly from between a pair of the blocks 18a, that is, from between one outside block and the intermediate block while the finger 20 extends outwardly from between the outside block and the intermediate block. The bolts 21—21 extend through the bracket 18 and blocks 18a and through bushings of insulation in the fingers 19 and 20.

One end of the finger 19 has the rearward extending lug 22 while one of the other fingers 19 has a lug 23. The conductor 14 extends to the lug 23, while a connection 24 ground is made from the lug 22. The fingers 19—19 are bridged as at 25 and with this bridge is engageable the contact 26 carried by the finger 21 normally when the fingers 19 remain unaffected by the feeler arm 16.

The base 17 is of slate or some other similar material but it is preferable that the blocks 28 and 29 be of brass. Monel metal is used on arm 16, its removable tip 30 and the pivot pin 31.

The feeler arm 16 has one end portion disposed through an opening in the block 29 and is suitably secured thereto, while depending from this block 29 is the pin 31 which seats in the recess 32 of the block 28, the block 28 having a pair of threaded bores 33 therein for receiving screws (not shown) for securing the block 28 to the base 17.

Obviously as each bottle 34 moves against the arm 16, the arm 16 is swung slightly so as to press against the bridge piece 34 at the outer ends of the arms 19 which flexes the arms 19 so as to remove its bridge piece 25 from the contact 26, on the free end of the arm 20 thus controlling whatever indicator or counter mechanism is desired.

Obviously the tip 30 can be of various materials such as felt, leather, Bakelite, brass, copper, etc.

It is furthermore to be understood, that this switch can be employed in counting systems for dropping pills or pellets, and as a matter of fact for counting cans, cartons and various other conveyor carried articles.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A switch of the character described comprising a base, a plurality of blocks of insulation mounted upon the base, a spring contact structure projecting outwardly from between a pair of said blocks, a second spring contact structure projecting outwardly from certain other of the blocks, said spring contact structures having opposed and normally engaging contacts, one of said spring contact structures being substantially longer than the other, an operator for the long contact structure, said operator comprising a block mounted on the base and having a recess extending downwardly therein from the top thereof, a second block disposed on the last-mentioned block and having a depending pin disposed in the recess, and an elongated feeler arm having one end portion disposed through the pin carried block and adapted to project well beyond the free end of the long spring contact structure, said feeler arm being adapted to be swung with its block by moving objects and to engage the long spring contact structure to flex the same and break its contacts with the contact of the other spring contact structure.

GEORGE WEIDER
CALVIN WILSON.
